UNITED STATES PATENT OFFICE.

WALTER S. ADAMS, OF PHILADELPHIA, PENNSYLVANIA.

DESIGN FOR AN AXLE-BOX FRAME.

SPECIFICATION forming part of Design No. 23,278, dated May 15, 1894.

Application filed March 20, 1894. Serial No. 604,459. Term of patent 14 years.

To all whom it may concern:

Be it known that I, WALTER S. ADAMS, a citizen of the United States, residing at Philadelphia, in the county of Philadelphia and State of Pennsylvania, have invented and produced a new and useful Design for Axle-Box Frames, of which the following is a specification.

The present design relates to the conformation of what is known in the art as an axle box frame, and the essential feature thereof lies in the shape or contour of the same.

In the drawings Figure 1 is a plan view, and Fig. 2 a side elevation.

This axle box frame is composed of the side bar extensions 1, 2 joined transversely by the end cross bars, 3, 4, the extensions joining the cross bars to inverted U shaped yokes, 5, 6, the parts 1, 2, extending from the lower por-

tion of the outer upright parts 7, 8 of the 20 yokes 5, 6, and from the inner upright parts 9, 10, of the yokes, and below the plane of the extensions 12, extend the central sections 11, 12. The yokes and central sections are wider in cross section than the extensions 1, 2, and 25 cross bars 3, 4. The frame in plan view is rectangular in shape.

Having described my invention, I claim—

The design for an axle box frame, substantially as herein shown and described. 30

Signed at Philadelphia, county of Philadelphia, and State of Pennsylvania, this 28th day of February, 1894.

WALTER S. ADAMS.
